Primary Examiner — Brett Miller*Assistant Examiner* — Rani J Abdallah(74) *Attorney, Agent, or Firm* — Eugene Vamos(57) **CLAIM**

The ornamental design for a beverage can cover, as shown and described.

DESCRIPTION

FIG. 1 is a front left perspective view of a beverage can cover that fastens to the lid of a beverage can;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a front left perspective view thereof showing fastened environmental structure.

The broken lines are for environmental purposes only and form no part of the claimed design.

1 Claim, 6 Drawing Sheets(56)
